CONTAINER CLOSURE

Winfred T. Parkin, Providence, R. I., assignor to
Theodore W. Foster & Bro. Company, Providence, R. I., a corporation of Maine

Application April 3, 1936, Serial No. 72,580

11 Claims. (Cl. 221—62)

This invention relates to container closures such, for example, as are used on cans, bottles, tubes, or similar receptacles containing powder or granular material to be dispensed in small quantities.

The principal objects of the invention are to provide a closure which is of simple design and of pleasing and attractive appearance, which is of economical construction, having but few parts, and which is inexpensive to manufacture, easy to assemble, and convenient to use; and to provide a closure which may be readily manipulated to control or vary the flow through the outlet and which sufficiently seals the outlet when in closed position so that there is no danger of the material accidentally leaking out, at least to any objectionable extent, when the container is not in use.

Further objects relate to various features of construction and will be apparent from a consideration of the following description and accompanying drawing; wherein,

Fig. 1 is a perspective view showing the top of a container having a closure member constructed in accordance with the present invention;

Figs. 2 and 3 are sections on the lines 2—2 and 3—3, respectively, of Fig. 1;

Fig. 4 is a perspective view of a closure of modified construction;

Figs. 5 and 6 are sections on the lines 5—5 and 6—6, respectively, of Fig. 4;

Fig. 7 is a perspective view of a further modification;

Figs. 8 and 9 are sections on the lines 8—8 and 9—9, respectively, of Fig. 7;

Fig. 10 is a sectional elevation of a container closure having a shutter of modified construction; and

Fig. 11 is a perspective view of the preferred form of shutter embodied in the constructions shown in Figs. 1 to 9, respectively.

The embodiment shown in Figs. 1 to 3 comprises a dome-like shell which may be of metal, celluloid or like material capable of being worked and of receiving and retaining an attractive finish. The top of the shell is formed with a wall portion 3 of cylindrical contour which defines a slideway on the inner surface of the shell, and this wall portion is provided with an outlet orifice, here shown as an aperture 5, and openings or slots 6 and 7 which are disposed in spaced relation on opposite sides of the aperture 5. Along each side of the slideway the shell is provided with inwardly struck protuberances 9 and 10 (Fig. 3) which are spaced below the margins of the slideway

proper to provide retaining flanges. The lower part of the shell is shaped to provide a skirt 12 which tightly fits about the neck or mouth of the container C (Fig. 1).

A shutter 15, consisting of a cylindrical sleeve or ring (Fig. 11), is rotatably mounted within the shell and is retained in position in the slideway formed between the top wall 3 and the protuberances 9 and 10. The shutter 15 is preferably of metal, celluloid or other material capable of being made into an elongate cylinder which may be cut up into rings of the desired width, as shown in Fig. 11, or of a resilient material which may be bent into the form of a cylindrical sector, 15^a, as shown in Fig. 10. In either case the shutter 15 is formed with an aperture 16 which conforms in size and shape to the aperture 5 in the shell, and outwardly extending nibs 18 and 19 are formed on opposite sides of the aperture 16; the nibs, apertures and openings in both the shell and the shutter being so constructed and arranged that when the shutter is assembled within the shell, the nibs 18 and 19 project outwardly through the openings 6 and 7, respectively, to provide finger pieces by means of which the shutter may be rocked or slid so as to bring the apertures 5 and 16 into and out of register.

In assembling the parts, the shutter is first positioned within the shell (preformed with the exception of the protuberances 9 and 10) and while the shutter is being held in position, the protuberances 9 and 10 are then struck inwardly by suitable dies, thus providing flanges which slidably support the shutter within the shell.

The embodiment shown in Figs. 4, 5 and 6 is substantially similar to the previously described embodiment, and the same reference numerals are used to designate like parts. In this embodiment the skirt 12 is provided with inwardly struck protuberances 22 and 23 (Fig. 5) adjacent to the lower ends of the slideway 3 so as to engage and slidably support the shutter 15, thus dispensing with protuberances 9 and 10, (Fig. 3) which extend along the side margins of the slideway, as shown in the previously described embodiment.

In the embodiment shown in Figs. 7, 8 and 9, the constructions are similar in all material particulars as in the embodiment shown in Figs. 1 to 6, except that the shutter 15 is slidably supported by a bridge 25, (Figs. 8 and 9) instead of inwardly struck protuberances. The bridge 25 consists of an arcuate member conforming to the curvature of the shutter and having upstanding ears 26 along its edges which engage and hold

the shutter in position, as shown in Figs. 8 and 9. The bridge 25 may be secured within the shell in any suitable manner, as for example an interior shoulder formed by an inwardly struck 5 circumferential rib 26 in the skirt 12 of the shell.

In each of the above embodiments, the shutter 15 is shown, by way of illustration, as a cylindrical shaped member, but it is to be understood that, if desired, the shutter may be in the form of a cylindrical segment or arc-like member 15^a, as shown in Fig. 10, in which case it may be secured in position in the same manner as shown in Figs. 1 to 9. If desired, headed pins, 15 rivets or the like members 30 may be used as finger pieces in place of the integral nibs 18 and 19, particularly where the shutter is made of celluloid or other material which does not possess the capability of being easily worked.

20 It will be noted that a closure constructed in accordance with the present invention may be easily opened or closed by the thumb or fingers of the hand holding the container to which it is attached, and that the closure may be adjusted 25 so as to regulate the flow of material through the aperture 5.

Instead of a single, comparatively large dispensing orifice formed by apertures 5 and 16, a number of smaller dispensing holes may be provided, especially when the closure is to be used for finely pulverized materials such as toilet powders. A series of small holes in the shutter corresponding in arrangement to a series of small holes in the top shell would be brought into and 35 out of register by rocking the shutter in the manner already described.

Although the closures above described are shown as forming the top of a rigid container C, it is to be understood that their utility is not limited for use with containers holding powdered or 40 granular material, as such closures may also be used with collapsible tubes containing tooth paste, grease and the like plastic or semi-fluid substances, and hence the term "container", as 45 herein used, is intended to include collapsible tubes as well as the various types of containers having rigid walls.

While I have shown and described different desirable embodiments of the invention, it is to be understood that this disclosure is for the purpose of illustration, and that various changes in shape, proportion and arrangement of parts, as well as the substitution of equivalent elements 50 for those herein shown and described, may be made without departing from the spirit and 55 scope of the invention as set forth in the appended claims.

I claim:

1. A container closure consisting of a shell of 60 fabricated sheet material and having a dome-like closed end defining a semi-cylindrical wall terminating in a continuous skirt adapted to fit the neck or mouth of a container, the width of said cylindrical wall being substantially less than the diameter or transverse dimension of said skirt, said cylindrical wall having at least one outlet 65 aperture and an opening therein, and a rotatable shutter having a semi-cylindrical part conforming with said wall disposed within said shell so that its cylindrical part snugly fits against said wall, said shutter having an outlet aperture and an outwardly projecting member which extends through said opening to provide a finger piece by means of which said shutter may be rotated back and forth so as to bring the outlet 70 apertures into and out of registry, said shell having inwardly struck protuberances constructed and arranged slidably to retain said shutter within said shell.

as to bring the outlet apertures into and out of registry, and means for rotatably retaining said shutter within said shell.

2. A container closure consisting of a shell of 75 fabricated sheet material and having a dome-like closed end defining a semi-cylindrical wall terminating in a continuous skirt adapted to fit the neck or mouth of a container, the width of said cylindrical wall being substantially less than the diameter or transverse dimension of said skirt, said cylindrical wall having at least one outlet aperture and an opening on each side of the outlet aperture, a rotatable shutter having a semi-cylindrical part conforming with said wall disposed within said shell so that its cylindrical part snugly fits against said wall, said shutter having an outlet aperture and outwardly projecting members on each side of said outlet aperture which extend through the corresponding openings in said wall to provide finger pieces by means of which said shell may be rotated back and forth so as to bring the apertures into and out of registry, and means for apertures retaining said shutter within said shell.

3. A container closure consisting of a shell of 80 fabricated sheet material and having a dome-like closed end defining a semi-cylindrical wall terminating in a continuous skirt adapted to fit the neck or mouth of a container, the width of said cylindrical wall being substantially less than the diameter or transverse dimension of said skirt, said cylindrical wall having at least one outlet aperture and an opening therein, a cylindrical shutter disposed within said shell so that a section of its periphery snugly fits against semi-cylindrical wall, said shutter having an outlet aperture and an outwardly projecting member which extends through said opening to provide a finger piece by means of which said shutter may be rotated back and forth so as to bring the outlet 85 apertures into and out of registry, and means for rotatably retaining said shutter within said shell.

4. A container closure consisting of a shell of 90 fabricated sheet material and having a dome-like closed end defining a semi-cylindrical wall terminating in a continuous skirt adapted to fit the neck or mouth of a container, the width of said cylindrical wall being substantially less than the diameter or transverse dimension of said skirt, said cylindrical wall having at least one outlet aperture and an opening therein, and a rotatable shutter having a semi-cylindrical part conforming with said wall disposed within said shell so that its semi-cylindrical part snugly fits against said wall, said shutter having an outlet aperture and an outwardly projecting member which extends through said opening to provide a finger piece by means of which said shutter may be rotated back and forth so as to bring the outlet 95 apertures into and out of registry, said shell having inwardly struck protuberances constructed and arranged slidably to retain said shutter within said shell.

5. A container closure consisting of a shell of 100 fabricated sheet material and having a dome-like closed end defining a semi-cylindrical wall terminating in a continuous skirt adapted to fit the neck or mouth of a container, the width of said cylindrical wall being substantially less than the diameter or transverse dimension of said skirt, said cylindrical wall having at least one outlet aperture and an opening on each side of the outlet aperture, and a cylindrical shutter disposed within said shell so that a section of its 105

periphery snugly fits against said semi-cylindrical wall, said shutter having an outlet aperture and an outwardly projecting member on each side of its outlet aperture extending through the corresponding opening in said semi-cylindrical wall, thereby to provide finger pieces by means of which said shutter may be rotated back and forth so as to bring the apertures into and out of registry, said shell having inwardly struck protuberances constructed and arranged slidably to retain said shutter within said shell.

6. A container closure consisting of a shell having a dome-like closed end defining a semi-cylindrical wall terminating in a continuous skirt adapted to fit the neck or mouth of a container, the width of said cylindrical wall being substantially less than the diameter or transverse dimension of said skirt, said cylindrical wall having at least one outlet aperture and an opening therein, and a rotatable shutter having a semi-cylindrical part conforming with said wall disposed within said shell so that its semi-cylindrical part snugly fits against said semi-cylindrical wall, said shutter having an outlet aperture and an outwardly projecting member which extends through said opening to provide a finger piece by means of which said shell may be rotated back and forth so as to bring the apertures into and out of registry, said dome-like end having inwardly struck protuberances extending along the edges of said semi-cylindrical wall for rotatably retaining said shutter within said shell.

7. A container closure consisting of a shell having a dome-like closed end defining a semi-cylindrical wall terminating in a continuous skirt adapted to fit the neck or mouth of a container, the width of said cylindrical wall being substantially less than the diameter or transverse dimension of said skirt, said cylindrical wall having at least one outlet aperture and an opening on each side of the outlet aperture, and a cylindrical shutter disposed within said shell so that a section of its periphery snugly fits against said semi-cylindrical wall, said shutter having an outlet aperture and an outwardly projecting member on each side of its outlet aperture and arranged to extend through the corresponding opening in said wall to provide finger pieces by means of which said shutter may be rotated back and forth to bring the apertures into and out of registry, said dome-like end having inwardly struck protuberances extending along the edges of said semi-cylindrical wall for rotatably retaining said shutter within said shell.

8. A container closure consisting of a shell having a dome-like closed end defining a semi-cylindrical wall terminating in a continuous skirt adapted to fit the neck or mouth of a container, the width of said cylindrical wall being substantially less than the diameter or transverse dimension of said skirt, said cylindrical wall having at least one outlet aperture and an opening therein, and a rotatable shutter having a semi-cylindrical part conforming with said semi-cylindrical wall disposed within said shell so that

its semi-cylindrical part snugly fits against said semi-cylindrical wall, said shutter having an outlet aperture and an outwardly projecting member which extends through said opening to provide a finger piece by means of which said shutter may be rotated back and forth so as to bring the apertures into and out of registry, said shell having inwardly struck protuberances adjacent to the ends of said semi-cylindrical wall for rotatably retaining said shutter within said shell.

9. A container closure consisting of a shell having a dome-like closed end defining a semi-cylindrical wall terminating in a continuous skirt adapted to fit the neck or mouth of a container, the width of said cylindrical wall being substantially less than the diameter or transverse dimension of said skirt, said semi-cylindrical wall having at least one outlet aperture and an opening therein, said shell having inwardly struck protuberances adjacent to the ends of said semi-cylindrical wall, and a cylindrical shutter disposed within said shell and slidably secured against said semi-cylindrical wall by said protuberances, said shutter having an outlet aperture and a finger piece which projects outwardly through said opening to provide actuating means for rotating said shutter back and forth so as to bring the apertures into and out of registry.

10. A container closure consisting of a shell having a dome-like closed end defining a semi-cylindrical wall terminating in a continuous skirt adapted to fit the neck or mouth of a container, the width of said cylindrical wall being substantially less than the diameter or transverse dimension of said skirt, said cylindrical wall having at least one outlet aperture and an opening therein, a rotatable shutter having a semi-cylindrical part conforming with said semi-cylindrical wall disposed within said shell so that its semi-cylindrical part snugly fits against said semi-cylindrical wall, said shutter having an outlet aperture and an outwardly projecting member which extends through said opening to provide a finger piece by means of which said shutter may be rotated back and forth so as to bring the apertures into and out of registry, and a bridge member secured within said shell so as rotatably to retain said shutter within said shell.

11. A dome-like shell having a wall portion of cylindrical contour defining a slideway and a continuous skirt portion below said slideway, said wall portion having an outlet aperture and an opening spaced therefrom, said skirt portion having a circumferential bead extending about its inner surface, a cylindrical shutter slidably mounted against said slideway, said shutter having an outlet aperture and an outwardly projecting part extending through said opening to provide a finger piece by means of which the shutter may be actuated, and a bridge member retained in position by said bead so as slidably to support said shutter.
